(57) **CLAIM**

The ornamental design for a swivel chair with underseat storage, as shown and described.

DESCRIPTION

FIG. 1 is a top left perspective view of the swivel chair with underseat storage of the present invention;

FIG. 2 is a front view thereof;

FIG. 3 is a left side view thereof;

FIG. 4 is a right side view thereof;

FIG. 5 is a top view thereof;

FIG. 6 is a top right perspective view thereof; and,

FIG. 7 is a top right perspective view thereof, illustrated with the seat in an open position.

The portions of the swivel chair with underseat storage illustrated in broken lines form no part of the claimed subject matter.

1 Claim, 7 Drawing Sheets
